John Cuccio, Westport, Conn., assignor to
Sybron Corporation, Rochester, N.Y.

Filed Nov. 15, 1971, Ser. No. 199,076

Term of patent 14 years

Int. Cl. D10—01

U.S. CL. D10—25

FIG. 1

FIG. 2

FIG. 3

FIG. 1 is a top plan view of a wall clock showing my new design;

FIG. 2 is a front elevational view thereof; and

FIG. 3 is a side elevational view thereof.

No rear view of the wall clock is shown or described because it is conventionally plain and unornamented.

I claim:

The ornamental design for a wall clock, substantially as shown and described.
